UNITED STATES PATENT OFFICE.

GWYLLYM R. HOLMES, OF BALTIMORE, MARYLAND.

MARINE TORCH.

1,296,664.

Specification of Letters Patent. Patented Mar. 11, 1919.

Application filed November 7, 1918. Serial No. 261,523.

To all whom it may concern:

Be it known that I, GWYLLYM R. HOLMES, a citizen of the United States, and residing at the city of Baltimore, State of Maryland, have invented certain new and useful Improvements in Marine Torches, of which the following is a specification.

The present invention relates to marine torches and more particularly to the type in which an illuminating gas is automatically generated and ignited when the torch is launched into water. Usually, such torches have two chambers, one containing the illuminant forming material and the other the igniting material, and the water is admitted to the chambers through independent openings. As these openings must be sealed when the torch is idle, it is necessary to provide means for breaking both seals when the torch is used. Furthermore, the opening for one of the chambers has usually been placed at the top of the torch, and as a consequence only small quantities of water enter the chamber and at irregular intervals, if at all. Thus where the opening for the igniter containing chamber is located at or near the top of the torch, and a material such as calcium phosphid is used, the small quantity of water entering causes a layer of lime to be formed on the phosphid, thereby preventing the formation of the igniting gas, and often the small amount of water entering the top is not sufficient to generate sufficient gas for igniting purposes.

It is the principal object of the present invention to remedy these defects. To this end the invention comprehends the provision of a single opening in communication with both the igniter chamber and the illuminant chamber, in consequence of which it is necessary to break a single seal only. A further feature resides in the location of this opening. Preferably it is positioned below the water line of the torch, so that sufficient water will always be supplied to the chamber when the torch is in the water.

Other objects and features of novelty will be apparent from the description taken in connection with the drawings, in which:—

Figure 1 is a sectional elevation of a torch constructed in accordance with the present invention;

Fig. 2 illustrates the manner of supporting the torch when used in connection with a life preserver;

Fig. 3 is a sectional elevation through the

illuminating gas burner shown in Fig. 1; and

Fig. 4 is a top plan view of a modified form of the invention, the cap covering the burners having been removed.

Referring to the drawings, the torch comprises a buoyant container 10, the bottom 11 of which carries a weight 12 to cause the torch to maintain an upright position when floating in the water. A vessel 13 is arranged within the container 10 and is designed to hold the igniter gas forming material 15, which usually is calcium phosphid. As shown, this vessel is cylindrical in form and has a tube 14 passing longitudinally through the same. A ring 16 has a nipple 17 screwed through the bottom 11 and the weight 12 and this nipple is extended through the bottom 18 of the vessel 13 and has the lower end of the tube 14 telescoped therein. The nipple 17 is hollow so that in effect it constitutes an extension of the tube 14.

The upper head 19 of the container may be formed with a dished portion 20 through which the upper end of the tube 14 projects, this end being open. An illuminating gas burner 21 is mounted in the dished portion 20 adjacent to the upper end of the tube 14. As shown in Fig. 3, this burner is preferably of the impinging type.

It will be seen that the annular space around the vessel 13 constitutes a chamber which is used for the purpose of holding an illuminating gas forming material 22 such as calcium carbid. It is one of the principal features of the present invention to utilize the opening through the nipple 17 for the purpose of supplying water to both the gas forming materials. To this end the pipes 23 are arranged in communication with the interior of the nipple 17 and extend through the illuminating gas material and are formed with apertures 24 for distributing water to the material. Within the vessel 13 the tube is formed with an opening 25 through its wall positioned near the bottom of the vessel and an opening 26 near the top thereof. Thus water entering through the nipple will pass through an opening 25 and coming in contact with the material 15 will generate an igniter gas which will rise and pass through the opening 26 to the upper end of the tube. If desired, other openings 25' may be formed near the openings 25.

When the torch is not in use it is neces-

sary to seal the opening through the bottom of the container, that is, the water inlet, so that moisture will not enter and effect deterioration of the gas forming material. As shown, this result is accomplished by forming the opening through the nipple 17 slightly smaller at its lower end as at 27, and a rod 28 closes this opening and extends throughout the length of the tube and projects from the upper end of the container. The top 19 may be formed with an upstanding flange 28' surrounding the dished portion 20 of the head, and the chamber thus formed may be closed by a head 29 which has a peripheral flange 30 engaging the outside surface of the flange 28'. The rod 28 projects through the head 29 and is formed with a ring 31 at its upper end and with a collar 32 bearing against the undersurface of the head 29. When the torch is used with a life preserver it is designed to be supported by means of the ring 31. Thus the entire weight is transmitted through the head 29 and this head is attached to the flange 28 in such a manner that it will support this weight and yet when the life preserver 33 is thrown into the water the head 29 will be torn off from the flange 28'. Such a fastening may be accomplished by weakly soldering the two parts together.

It will be observed that when the torch is torn from its fastening or supporting means, not only will the cap 29 be removed, but the rod 28 will be drawn upward and out of the tube, thereby unsealing the opening 27. Hence, when the torch is launched into the water the opening 27 being free the water will enter therethrough and be distributed to the two chambers thereby generating the igniter gas in the vessel 13 and an illuminating gas in the chamber 33. The igniter gas issuing from the upper end of the tube 14 will burn upon coming in contact with the air and will ignite the illuminating gas issuing from the burner 21. The torch will float in an upright position in the water in the usual manner and as the water inlet for both chambers is disposed below the water line sufficient water will be supplied to continuously generate gases in both chambers.

In the form of the invention illustrated in Fig. 4, instead of using a burner such as 21 illustrated in Fig. 1, the dished portion 20' of the head is formed with a series of openings 21' disposed around the upper end of the tube 14, and the illuminating gas issuing through these openings is ignited by the gas burning at the upper end of the tube.

Although an embodiment of the invention has been described specifically it is to be understood that the invention is not so limited but includes modifications and changes which come within the scope of the appended claims.

Having thus described the invention what

is claimed as new and desired to be secured by Letters Patent is:—

1. A marine torch including a container having two separate chambers, one adapted to hold the igniter gas forming material and the other the illuminating gas forming material, both gases being generated by the addition of water, said container having an opening through one of its walls in communication with each of said chambers, said chambers being disposed so that water entering through said opening will flow to both the chambers when the container is placed in water, and releasable means normally closing said opening. 80

2. A marine torch including a container having two separate chambers, one adapted to hold the igniter gas forming material and the other the illuminating gas forming material, both gases being generated by the addition of water, said container having an opening through its bottom wall in communication with each of said chambers, said chambers being disposed so that water entering through said opening will flow to both the chambers when the container is placed in water, and releasable means normally closing said opening. 85

3. A marine torch including a container having two separate chambers, one adapted to hold the igniter gas forming material and the other the illuminating gas forming material, both gases being generated by the addition of water, said container having an opening through one of its walls in communication with each of said chambers, said chambers being disposed so that water entering through said opening will flow to both the chambers when the container is placed in water, said opening being below the level 95 of the water, and releasable means normally closing said opening. 100

4. A marine torch including a buoyant container having two separate chambers, one adapted to hold the igniter gas forming 110 material and the other the illuminating gas forming material, both gases being generated by the addition of water, said container having an opening through one of its walls in communication with each of said chambers, said chambers being disposed so that water entering through said opening will flow to both the chambers when the container is placed in water and means sealing said opening, adapted to be rendered inoperative by launching the torch. 115

5. A marine torch including a buoyant container having two chambers, a portion at least of each chamber being below the water line, one chamber adapted to hold the igniter gas forming material and the other the illuminating gas forming material, both gases being generated by the addition of water, below the water line, means to admit water to said chambers, and means to seal 125 130

- said water admission means, adapted to be rendered inoperative by launching the torch.
6. A marine torch including a buoyant container adapted to hold illuminating gas forming material, a centrally disposed vessel within said container adapted to hold igniter gas forming material and having at least a portion below the water line, a water inlet in the bottom of the container having communication with the interior of the container and vessel, means to close said inlet, and means extending from the top of the container through said vessel to open said inlet when the torch is launched.
- 15 7. A marine torch including a buoyant container, a vessel within said container, a

tube extending from the top of the container through the bottom thereof and open at its lower end, said tube having an opening in its wall communicating with the interior of the container and two openings communicating with the interior of the vessel, one being near the bottom and the other the top of the vessel, an illuminating gas burner at the top of the container adjacent the upper end of the tube, a cap inclosing the burner and upper end of the tube, means to close the lower end of the tube, and means actuated by launching the torch to remove said cap and open the lower end of the tube.

In testimony whereof I affix my signature.
GWYLLYM R. HOLMES.
